UNITED STATES PATENT OFFICE.

ALFRED F. MCCOLLUM, OF BLOOMSBURG, PENNSYLVANIA.

METHOD AND MACHINE FOR PRINTING PILE FABRICS.

1,377,083.

Specification of Letters Patent.

Patented May 3, 1921.

Application filed May 13, 1920. Serial No. 381,027.

To all whom it may concern:

Be it known that I, ALFRED F. McCOLLUM, a citizen of the United States, residing in Bloomsburg, Columbia county, Pennsylvania, have invented the Method and Machine for Printing Pile Fabrics, of which the following is a specification.

One object of this invention is to provide a novel method of and machine for applying 10 coloring matter to pile and flat fabrics such as rugs, carpets and the like, whereby such material shall be transferred to or delivered to the greater part of the length as well as to the ends of the pile fibers or threads, or 15 if the fabric be of the flat weave type, to the body of the fabric, with a view to producing a clear, permanent design which will be retained with practically its full brilliancy for the life of the fabric.

20 My invention further contemplates a novel method and machine for printing a continuous length of woven fabric either uncolored or having but a single color so that after treatment it may be cut into a series of 25 lengths or sections each constituting a complete article of manufacture having any normally colored design, the coloring material being applied to the main or body portions as well as the outer part or surface of the 30 fabric.

My invention further contemplates a machine of the above noted type which shall include means for propelling through it the length of fabric under treatment so arranged as to engage said fabric at predetermined points between successive printed sections so that the latter are not injured by said means.

Another object of my invention is to provide 40 a fabric printing machine which shall, while utilizing an intermittently acting apparatus for applying coloring material, be capable of including a continuously acting device for distributing the previously applied coloring matter in accordance with the 45 invention.

These objects and other advantageous ends I attain as hereinafter set forth, reference being had to the accompanying drawings, in 50 which.

Figure 1 is a plan of a portion of a length

of pile fabric in which a part is shown as having been printed in accordance with my invention;

Fig. 2 is a side elevation, to some extent 55 diagrammatic, illustrating the machine forming part of my invention;

Fig. 3 is a fragmentary elevation illustrating the action of part of the machine;

Fig. 4 is a vertical section of a body of 60 fabric also to some extent diagrammatic and on an enlarged scale, further illustrating the operation of my method and machine; and

Fig. 5 is an enlarged fragmentary view, 65 illustrating the action of the parts shown in Fig. 3; and

Figs. 6 and 7 are respectively a vertical section and a plan, both to some extent diagrammatic, showing the construction of the propelling apron and certain of its associated parts. 70

I have discovered that coloring matter such as it is possible to employ in the color designs of textile fabrics such as rugs, carpets, velvets and the like, can be successively 75 applied to or made to take upon the entire length of the pile fibers as well as upon their ends or upon the body or base portions of the fabric by first applying said material to the ends of the fibers or surface of the 80 fabric and then subjecting it to a rolling action so that the coloring material that each fiber or adjacent series of fibers carries on its ends or outer surface is delivered to the body portions of one or more other fibers all the 85 way from the base structure or body of the fabric in which it is held, to its own color bearing end. Thereafter when the fibers are permitted or caused to return to their original straight positions substantially at right 90 angles to the plane of the body of the fabric, each of them has the color material upon it for its entire length and this quite regardless of its length.

In carrying out my invention on a commercial scale I have found it possible to weave a fabric in the form of a continuous length of web preferably divided by headings into a succession of sections constituting uncolored or single colored rugs, carpets 100 or the like. Such a fabric web or length may then be run through a suitable form of

printing machine whereby its various parts have different colors applied to them in the form of a predetermined ornamental design, the machine as usual merely depositing the 5 colored materials in a liquid or semi-liquid condition upon the end portions or surface of the fabric.

Thereafter the printed length of fabric is run through a machine whereby if it has a 10 pile, its pile fibers are successively bent over so that the end of each of them with its globule or small mass of coloring material is drawn over or applied to all or a part of the projecting body portion of one or more 15 other pile fibers so as to transfer to it a greater or less amount of said material, and this operation may be repeated any desired or required number of times necessary to color each fiber for its entire length, after 20 which the fabric may be subjected to any further treatment necessary to fix the coloring material or otherwise finish the treatment in any of the ways common in the rug or carpet printing art. In the case of a fabric of the flat weave type the color carrying threads or fibers are squeezed out or flattened so that the coloring material is delivered to the body or lower portions of the fabric.

30 In carrying out my invention I preferably weave a continuous length of fabric so that it consists of a series of sections 1 separated by relatively narrow headings 2 and make it either of uncolored yarn or of 35 a yarn of uniform color. After being printed in accordance with my invention, the various sections have the appearance indicated at 1^a and may be separated by cutting through their heading portions 2.

40 In order to apply the coloring matter as above indicated I supply a length of fabric 3 from a source such as the roll 3^a and pass it through any suitable machine 5 for applying coloring material in the form of 45 ornamental designs. This machine in the present instance is illustrated as having a frame 6 including supports for an endless driving band or apron 7 having propelling pins or other devices 7^a mounted on its cross 50 rails 7^b and projecting at such intervals as to engage only the heading portions 2 of the web 3 between printed portions thereof. The printing machine illustrated includes a series of vertically reciprocating carriers 55 4 supporting printing blocks 4^a for applying the coloring material to the fabric in the desired designs and said material is supplied to the blocks from fountains 8 or the like in the manner well understood in the printing 60 art.

As illustrative of the detail construction of a machine which may be utilized for printing a fabric as indicated, that described and claimed in the patent to William H.

Waldron #1,145,821, dated July 6, 1915, 65 will produce the desired results, so that the length of material is intermittently delivered from the machine with the coloring material applied in the desired designs to its pile or other surface or to the ends of 70 the pile fibers and in amounts regulated to obtain the desired results when the fabric is subjected to the treatment hereafter described.

From the machine 5 the printed fabric 3 75 is allowed to fall in a loop or loose length, from which it passes over the surface of a relatively large drum 9 continuously driven at such a speed as to take it away without permitting the periodic variation in the 80 length of the loop to materially change. Coacting with this main roller 9 are a series of parallel relatively smaller rollers 10, 11 and 12 so designed as to press down the pile or other fibers of the fabric as this is passed 85 between them and the roller 9. These rollers 10, etc., are provided with wipers or doctors 13 designed to remove from their surface any coloring matter received from the fabric and deposit this within suitably mounted receptacles 14.

In Fig. 5 I have diagrammatically illustrated the operation upon a pile fabric of the color distributing machine constituted by the rollers 9, 10, 11 and 12 and from this figure it will be seen that a series of pile fibers as *a* running transversely of the length of the fabric as it passes from the machine 5, carries on its outer surface a mass or film *b* of coloring matter. Hitherto, it has been found impossible to cause this material to completely and uniformly penetrate the body of the pile so as to color the bodies or entire length of the successive 95 series of pile fibers, although when in accordance with my invention, a series of fibers such as that indicated at *c* is engaged by or comes into contact with the roller 10 or equivalent pressure device, it is inclined from a position at right angles to the body 100 of the fabric so that some of the coloring material carried by the ends of its fibers strikes and is transferred to some of the fibers of the adjacent series *a* at points below their ends. 110

As each series of pile fibers is more and more bent over toward the body 15 of the fabric, the film of coloring material carried by its ends is squeezed into or delivered to the hitherto uncolored bodies of the fibers 115 of one or more adjacent series as indicated at *d*, *e*, *f*, and *g*. As the fabric passes out from between the rollers 9 and 10, each series of pile fibers *h*, *i*, *j* and *k*, by reason of its natural elasticity, returns toward its 120 original position perpendicular to the body or back 15 and I have noted that each of said series is then completely colored from 125

the ends to the bases of its pile fibers. After being subjected to steaming and other treatments well known in this art, the finished fabric is found to be printed with 5 the desired design which extends all the way from the top of the pile to the base thereof.

Similarly flat weave fabrics such as tapestry or round wire fabric may be advantage- 10 ously treated according to my invention as above described for the coloring material is thus transferred or caused to penetrate the body or filling threads so as to cause the color design to be present in or applied to 15 all or any desired part of the fabric structure,

In order to carry out my invention I preferably apply the coloring material in a lather-like condition, so that it is transferred 20 from the printing blocks to the fabric in a film of any desired thickness. When therefore the printed fabric is subjected to a subsequent rolling operation, there is sufficient coloring material present 25 to penetrate and color the entire body or any desired part thereof, with the applied design.

It is to be noted that if and when desired 30 the amount of applied coloring may be increased either by providing a number of printing blocks to apply the same color or by so operating the machine as to cause one or more blocks to make a plurality of im- 35 pressions while the fabric is held from forward movement.

I claim:-

1. The method which consists in applying coloring material to the surface of a pile fabric; and thereafter mechanically operating 40 on the pile of said fabric to cause such coloring material to be transferred from the ends of its pile fibers to the bodies thereof.

2. The method which consists in applying 45 coloring material to the end portions of the pile of a pile fabric; and thereafter bending the pile fibers of said fabric to cause coloring material on the ends thereof to be transferred to the bodies of adjacent 50 pile fibers.

3. The method which consists in printing 55 pile fabric in a colored design; thereafter operating on the fibers constituting said pile to cause coloring material carried by their end portions to be applied to the body portions of adjacent pile fibers.

4. The method which consists in printing 60 a colored design on a pile fabric; and thereafter subjecting the pile of the fabric to a rolling action to bend its fibers and to bring its end portions into proximity to the body portions of other pile fibers so as to transfer coloring material to the latter.

5. The method which consists in intermit-

tently printing a design upon a pile fabric; 65 and thereafter continuously operating on the pile of said fabric to cause coloring material upon the ends of its pile fibers to be transferred to the bodies of adjacent pile fibers.

6. The method which consists in applying 70 coloring material in a definite design to the end portions of the pile fibers of a pile fabric; and subjecting the pile of the fabric to a succession of bending opera- 75 tions whereby coloring material upon the end portions of its fibers is transferred to the bodies thereof.

7. The method which consists in success- 80 sively printing the sections of a length of pile fabric with the same colored design; and thereafter subjecting said fabric to an operation whereby its pile fibers are inclined to cause their color bearing end portions to be brought adjacent and transfer 85 coloring matter to the body portions of other pile fabrics.

8. The method which consists in applying 90 coloring material to the surface of a fabric; and thereafter mechanically operating on said fabric to cause such coloring material to be transferred from its surface to its main portions.

9. The method which consists in printing 95 a design on a fabric; and thereafter subjecting said fabric to a rolling action to transfer the material of said design from its surface to its inner portions.

10. The method which consists in applying 100 to a fabric a film of coloring material; and thereafter subjecting said fabric to a rolling operation to cause the material of said film to penetrate its body.

11. The method which consists in applying 105 to a fabric a lather-like film of coloring material; and thereafter subjecting said fabric to a rolling operation to cause the material of said film to penetrate its body.

12. The combination of means for applying 110 coloring material to the end portions of the pile of a pile fabric; and means for bending over the fibers of said pile to cause coloring matter carried by the end portions to be transferred to the body portions of other fibers.

13. The combination of an intermittently 115 acting machine for printing a design on the pile of a pile fabric; with a continuously acting device for causing the coloring matter deposited by said printing machine to be applied to the body portions of the pile fibers of said fabric.

14. The combination of a machine for 125 printing a colored design on a pile fabric; a supporting structure for receiving the fabric after it has been printed; and at least one member for bending the pile fibers down toward the body of the fabric to cause the

coloring matter carried by their end portions to be transferred to their body portions.

15. The combination of a machine for printing colored designs on pile fabric; with a main supporting roller and at least one roller mounted to coöperate with said main roller to bend over the pile of the fabric and to cause the coloring material on the end portions of its pile fibers to be transferred to the body portions thereof.

16. The combination of means for apply-

ing coloring material to the surface of a fabric; and a mechanical device for thereafter transferring said material from the 15 surface to the interior portions of said fabric.

17. The combination in a fabric printing machine of printing blocks; a web propelling apron having cross members; and pins 20 in said members positioned to engage portions of the fabric lying between the portions operated on by said blocks.

ALFRED F. McCOLLUM.
